FIG. 3.

Inventor

By his Attorney George Finn
Chat C. Gile

UNITED STATES PATENT OFFICE.

GEORGE FINN, OF NEWARK, NEW JERSEY.

DESIGN FOR A GAS-STOVE TOP.

53,439.

Specification for Design. Patented June 17, 1919.

Application filed March 30, 1918. Serial No. 225,822. Term of patent 14 years.

To all whom it may concern:

Be it known that I, GEORGE FINN, a citizen of the United States, residing at Newark, in the county of Essex and State of New Jersey, have invented a new, original, and ornamental Design for a Gas-Stove Top, of which the following is a specification, reference being had to the accompanying drawings, forming a part thereof, and in which:

Figure 1 is a top view;

Fig. 2 a side elevation, and
Fig. 3 a rear end view of a gas stove top
embodying my design.

I claim:

The ornamental design for a gas stove top,
as shown.

GEORGE FINN.

Witnesses:

ARTHUR MARION,
CHAS. C. GILL.
